UNITED STATES PATENT OFFICE

170,825

COMBINED RAZOR AND SHAVING CREAM DISPENSER

Elmer S. Lovasz, Chicago, Ill.

Application May 4, 1953, Serial No. 24,821

Term of patent 14 years

(Cl. D22—3)

To all whom it may concern:

Be it known that I, Elmer S. Lovasz, a citizen of the United States, residing in Chicago, in the county of Cook and State of Illinois, have invented a new, original, and ornamental Design for a Combined Razor and Shaving Cream Dispenser, of which the following is a specification, reference being had to the accompanying drawing forming a part thereof, in which:

Fig. 1 is a perspective view of a combined razor and shaving cream dispenser, showing my new design; and

Fig. 2 is a side elevational view thereof.

The side opposite to that disclosed in Fig. 1 presents a substantially similar appearance as the side disclosed.

The dominant features of my design reside in the portions shown in full lines.

I claim:

The ornamental design for a combined razor and shaving cream dispenser, substantially as shown and described.

ELMER S. LOVASZ.
